UNITED STATES PATENT OFFICE

2,053,922

MINE CAR

Walter H. Statler, Johnstown, Pa., assignor to
Bethlehem Steel Company, a corporation of
Pennsylvania

Original application January 6, 1932, Serial No.
585,015. Divided and this application May 22,
1934, Serial No. 726,907

5 Claims. (Cl. 214—54)

My invention relates to the construction of mine cars and more especially to that type of mine car which is equipped with a swinging end gate that is automatically latched when closed and which is adapted to be automatically tripped to open for the purpose of releasing the car loading as it arrives at the unloading bins or chutes. This application is a division of my co-pending application filed January 6, 1932, Serial No. 585,015.

An object of my invention is to provide means in combination with an end-gate latching mechanism which first automatically engages the latch operating means provided at the unloading bins or chutes for the purpose of unlatching the end-gate, and thereafter automatically disengages the latch operating means as the car assumes its unloading position.

Other objects of my invention relate to certain novel features of construction, combination, and arrangement of parts which will be hereinafter more fully described and particularly pointed out in the appended claims, reference being had to the accompanying two sheets of drawings in

which:

Fig. 1 is a side elevation of a mine car embodying my improvements;

Fig. 2 is a front elevation of the same car;

Fig. 3 is a part horizontal section taken along the line 3—3 of Fig. 2; and

Fig. 4 is a part vertical section taken along the line 4—4 of Fig. 2.

In the drawings the numeral 10 indicates the mine car in which is embodied my improvements, and in Fig. 1 the mine car 10 is shown in position at the automatic unloading point of the tipple. The automatic unloading means is not a part of my invention and any arrangement would be suitable which would comprise a car tilting device such as the tilting platform 11, and a latch operating mechanism such as the biased lever device 12, shown diagrammatically in Fig. 1.

The car 10 comprises the car sides 13 attached to which on the inside of the front upper corners are the shaft support brackets 14. The brackets 14 extend above the top edge of the sides 13 and are adapted to receive the shouldered and threaded ends 15 of the shaft 16. The shaft 16 is secured in the brackets 14 by the cottered nuts 17, and by reason of the shouldered engagement, the shaft 16 acts to maintain the upper front corners of the sides 13 in rigid spaced relation.

The front end of the car 10 is closed by a swinging end or door 18. The door 18 comprises

a steel plate 19 having its upper edge bent or rolled over to the outside to form a tubular top edge 20 with the edge 21 bent flat against the outside of the door plate 19 and riveted thereto, while its lower edge is similarly bent but in an opposed direction. Riveted on the inside face of the plate 19 at the top are the hinges 22 which in turn are pivotally mounted upon the shaft 16. Collars 23 functionally integral with the shaft 16 engage opposed faces of the outer pair of hinges 22, thus positioning the door 18 in relation to the sides of the mine car 10. For stiffening purposes angle bars 24 at the ends and a pressed steel recessed plate or stake 25 at the vertical center are riveted to the inside face of the plate 19. For latching the door 18, the keeper plates 26 are riveted to the outside of the mine car sides 13 at the lower front corners. On the front face of the plate 19 at the lower corners are riveted the latch guides 27 which guide the outer ends 20 of the substantially horizontal latches 28 while their inner ends are pivotally attached to a vertical latch slide bar 29 by suitable means 30. The latch slide bar 29 is slidably mounted in the guides 31 and 32 riveted to the outside face of the plate 19 on the vertical center. The upper end 33 of the latch slide bar 29 is bent outward for a purpose to be hereinafter described. Also riveted on the outside face of the plate 19 on either side of the vertical center and just above the guide 31 are the cam brackets 34 having the upward and outward sloping edges 35, the purposes of which will hereinafter be described.

Having thus described the structure of my mine car I will now describe its operation upon its assumed arrival at the tipple loaded and ready to be unloaded. The car 10 as loaded is run onto a car tilting device 11 at the unloading point which may, in the tilting platform type shown diagrammatically in Fig. 1, include stops 36 for the car 10 wheels 37. As the car wheels 37 engage the stops 36 the arrested momentum of the loaded car tends to tilt the car 10 and the platform 38 forward about the pivot point 39 until they come to rest at a suitable unloading angle by engaging a stop not shown. At the instant the car wheels 37 engage the stops 36 the upper end 33 of the latch slide bar 29 comes into engagement on its under side with the suitably adapted end 40 of the biased lever device 12 (shown diagrammatically) pivotally mounted to the structure 41 of the tipple. The action of the biased lever device 12 in engagement with the latch slide bar 29 is such that as the car 10 tilts forward about the platform tilting point 39 the latch slide bar 29 is raised, relatively

to its initial position on the front door 18, which action results in withdrawal of the latches 28 from engagement with the keeper plates 26. As the latches 28 disengage, the weight of the coal 5 against the swinging door 18 causes the latter to swing outward and thus give ready exit to the unloading coal. As the car 10 continues to tilt downward in its unloading operation after the latches 28 are disengaged and the door 18 has 10 swung open, it is desirable that the biased lever device 12 having done its work to be disengaged. This is brought about by the outward sloping edges 35 of the cam brackets 34 engaging the end 15 40 of the biased lever 12 and gradually disengaging the latter from the latch slide bar end 33. When the point of disengagement is reached as shown in dotted lines in Fig. 1 the latch slide bar 29 drops due to the action of gravity to its initial position shown in Fig. 2. This also returns the 20 latches 28 to their initial position. When the car is unloaded and is returned to a horizontal position, the door 18 tends, due to the action of gravity, to return to its closed position, and this return movement brings the outer ends of the latches 28 25 into engagement with the sloping edges 42 of the keeper plates 26. Since the latches 28 are pivotally attached to the latch slide bar 29 at 30 they are free to rise along the slopes 42 in the guides 27 until the door 18 becomes closed, when the 30 latches 28 then drop into latched engagement with the keeper plates 26 as shown in Fig. 1. The car 10 is then again ready to be loaded.

Although I have described and illustrated my invention in considerable detail, I do not wish to be limited to the exact and specific details thereof, as shown and described, but may use such modifications in, substitutions for, or equivalents thereof, as are embraced within the scope of my invention or as pointed out in the claims.

Having thus described my invention what I claim as new and desire to secure by Letters Patent is:

1. In combination with apparatus for automatically releasing an end-gate and for tilting a car to unload, a front end dump mine car comprising car body side walls, brackets fixed to upper front outside corners of said side walls, keeper plates fixed to lower front outside corners of said side walls, a front end-gate pivotally attached to said 45 brackets, a latch device operably mounted on said end-gate adapted to engage said keeper plates to hold said end-gate closed when the car is in a normal loaded position and to automatically engage said releasing apparatus when the 50 car is tilted forward to unload, and a cam device fixed to said end-gate to automatically disengage the releasing apparatus when the car is in the 55

unloading position, and said end-gate so pivotally attached to said brackets that gravity returns the end-gate to a latched condition upon returning the car to the loading position.

2. In combination with apparatus for automatically releasing an end-gate and for tilting a car to unload, an end dump mine car comprising car body side walls, and end-gate hinged to said side walls, a latch for locking said end-gate closed when in a normal operating position including 10 means adapted to engage said releasing apparatus when the car is first tilted to unload, and cam means functionally integral with said end-gate for automatically disengaging the releasing apparatus upon continued tilting to unload. 15

3. In combination with apparatus for automatically releasing an end-gate and for tilting a car to unload, an end dump mine car comprising car body side walls, an end-gate hinged to said side walls, end-gate latching means adapted to engage 20 said releasing apparatus when the car is tilted to unload, and cam means functionally integral with said end-gate for disengaging the said releasing apparatus upon the car assuming its unloaded 25 position.

4. In combination with apparatus for automatically releasing an end-gate and for tilting a car to unload, an end dump mine car comprising car body side walls, hinge means and latch keeper means fixed to said side walls, an end-gate attached to said hinge means, a latch device operably mounted on said end-gate adapted to engage 30 said keeper means in normal loaded position of the car and to automatically engage said releasing apparatus when the car is tilted to unload, and means to automatically disengage the said releasing apparatus when the car is in the unloading position. 35

5. In a mine car structure, the combination of 40 car body side walls, an end-gate hinged to said side walls, keepers fixed to said side walls, latch guides and latch slide guides fixed to said end-gate, a latch slide vertically slidably mounted in said latch slide guides, substantially horizontal latches adapted to engage said keepers at their 45 outer ends and to have translational movement co-planar with the end-gate in the said latch guides, and to be pivotally attached to the said latch slide, the said latch slide having a projecting portion adapted for operable engagement for 50 the purpose of lifting said latches, and cams mounted on said end-gate in juxtaposition to said projecting portion whereby operable engagement with the projecting portion is broken when the 55 latch slide is fully lifted.

WALTER H. STATLER.
